DESIGN FOR DECORATIVE PAPER

Marie Orth, Jamaica, N. Y., assignor to Trautmann, Bailey & Blampay, New York, N. Y., a corporation of New Jersey

Application March 16, 1937, Serial No. 68,184

Term of patent 3½ years

To all whom it may concern:

Be it known that I, Marie Orth, a citizen of the United States, residing at Jamaica, county of Queens, in the State of New York, have invented a new, original, and ornamental Design for Decorative Papers, of which the following is a specification, reference being had to the accompanying drawing, forming part thereof.

The figure is a plan view of the paper, showing my new design.

I claim:

The ornamental design for decorative paper, as shown.

MARIE ORTH.
